(57) **CLAIM**

The ornamental design for an apparatus for medical or laboratory diagnosis, as shown and described.

DESCRIPTION

FIG. 1.1 is a perspective view of an apparatus for medical or laboratory diagnosis with the screen in a first position showing our new design;

FIG. 1.2 is a front view thereof;

FIG. 1.3: is a back view thereof;

FIG. 1.4 is a left view thereof;

FIG. 1.5 is a right view thereof;

FIG. 1.6 is a top view thereof;

FIG. 1.7 is a bottom view thereof;

FIG. 1.8 is a perspective view of the apparatus for medical or laboratory diagnosis with the screen in a second position; and

FIG. 1.9 is another perspective view of the apparatus for medical or laboratory diagnosis with the screen in a third position.
